UNITED STATES PATENT OFFICE.

FERDINAND E. CANDA, OF NEW YORK, N. Y.

BALL-MILL.

1,337,641.

Specification of Letters Patent. Patented Apr. 20, 1920.

Application filed May 13, 1916. Serial No. 97,224.

To all whom it may concern:

Be it known that I, FERDINAND E. CANDA, a citizen of the United States of America, and a resident of New York, in the county 5 of New York and State of New York, have invented a certain new and useful Ball-Mill, of which the following is a specification.

My invention relates to ball mills of the 10 type used for crushing rock, ore and other substances, and comprises a novel construction of shell for such mills and other features as hereinafter described and particularly pointed out in the appended claims.

15 As such mills have been generally constructed heretofore, the shell itself has been a member separate and distinct from the wearing face of the mill, such wearing face consisting of a hollow member insert-

20 ed within and held in place in the shell proper; and this shell proper has commonly been formed in two members, each cylindrical and each having formed integrally with it one of the heads of the mill; the

25 two members of the shell parting at the center of the mill in a plane of rotation of the shell. To this construction there are various objections. At the discharge head of the mill there are usually certain radial

30 members forming a support for the grating or screen of the mill, and which should be machined to afford an even support for the grating; but the depth of the shell is such that it is impracticable to ma-

35 chine such radial members by ordinary tools, for which reason they are usually left unmachined, and therefore uneven, and therefore the grating is not evenly supported, for which reason much wear of the

40 grate members may occur and breakage of the grate members may also occur. Also there is much leakage through the bolt holes through which pass the bolts connecting the wearing member to the shell. A fur-

45 ther objection of the old construction of mill referred to is that the said wearing face of the mill must be a cast member, whereas if this wearing face may be formed of rolled members of hard steel, such for

50 example as chrome steel, they will be much more durable.

By my present invention I avoid occasion for use of a wearing face or member separate and distinct from the shell itself; 55 the shell itself, the inner surface of which is also the wearing face, is formed of seg-

ments which may be fastened together to complete the shell and also the wearing face, and these segments are of such form that they may be rolled; the heads of the mill 60 are separate from the shell segments, and therefore may be machined readily; access to the interior of the mill may be gained readily by removal of one of the heads of the mill; the several segments constituting the 65 shell of the mill, and also its wearing face, are so fastened together that a rigid structure is produced; and that passage of dust or mud through the joints between the segments is obviated; also the mill as a whole 70 is lighter, for equal service and capacity, than the former mills above referred to. Other features of my invention will be pointed out hereafter.

The objects of my invention are, to improve the construction of ball mills, particularly mills of the type referred to; to make the wearing face of the mill of such construction that its parts may be produced by rolling or pressing, and therefore may be formed of steel or other very hard material which nevertheless possesses the grain and fiber characteristic of metal which has been worked, as distinguished from cast metal; to construct the said wearing member in such manner that it may also form the shell of a mill, dispensing with any separate shell; to so arrange and construct the parts of this wearing member that such parts are readily assembled, and 85 when assembled form a rigid structure through the joints of which dust and mud will not escape; to so construct the mill that the heads thereof are readily separable from the shell proper, which heads may 90 therefore be machined readily; to attach these heads to the shell proper in a secure yet simple manner; and to make the mill of lighter weight, for equal size and service, 95 than former mills of similar type.

I will now proceed to describe my invention with reference to the accompanying drawings and will then point out the novel features in claims.

In the drawings:

Figure 1 shows in part a fragmentary end view, looking from the charging end of the mill, and in part a fragmentary transverse section of the mill, showing segments of the grate.

Fig. 2 shows a fragmentary transverse section of a mill similar to that shown in

105

110

Fig. 1, but embodying an alternative construction of shell, two grating sections only being shown, and a portion of the discharge head of the mill being shown in elevation.

5 Fig. 3 shows a fragmentary axial section of the discharge end portion of a mill such as shown in Fig. 1, the section being taken on the section line 3—3 of Fig. 1.

Fig. 4 shows a fragmentary axial section 10 of the discharge portion of a mill such as shown in the previous figures, the section being taken on the section line 4—4 of Fig. 2.

Fig. 5 shows in part an axial section of 15 the charging end of a mill such as shown in Fig. 1, and in part a side elevation of the discharge end of the mill, one of the rows of coating lugs on the exterior of the mill being sectioned in a plane parallel to 20 the axis of the shell, to show the inserted key.

Fig. 6 is a fragmentary section on the line 4—4 of Fig. 2, but on a larger scale than Fig. 4, and shows particularly the means 25 for pressing the grate bars together.

Fig. 7 is a detail side view of one of the wedge-headed bolts shown in Figs. 4 and 6, and in other figures of the drawings.

Fig. 8 is a fragmentary detail sectional 30 view, the section being taken on the line 8 of Fig. 1, and shows improved means for clamping the grate bars at their ends.

Referring first to Figs. 1, 3, 4 and 5: 1 designates the shell of the mill, 2 the receiving head of the mill, 3 the discharge head thereof, 4 the hollow trunnion of the receiving end of the mill and 5 the hollow trunnion of the discharge end of the mill. It will be understood that the structure 40 1—2—3, is adapted for mounting in suitable bearings for rotation, the hollow trunnions 4 and 5 constituting the journals; also that the structure 1—2—3 will be provided with means of customary nature for rotating it, which means are not shown in the drawings. The shell 1 is formed of segments 1^a provided at their meeting faces with lugs 6 having registering apertures for the passage of suitable fastening bolts 50 7. These segments 1^a are provided, on their interior faces, with suitable rises 8, forming the usual ribs which cause the crusher balls, (not shown in the drawings, since they form no portion of the present invention) to lift 55 and then fall on rock in the spaces between these rises. The segments 1^a therefore form both the shell of the mill and the wearing member. That these segments 1^a may be fitted together accurately and rigidly, and 60 that passage of dust or mud through the joints of the segments may be prevented, the meeting faces of the various segments 1^a are provided with key grooves 9 and suitable keys 10 are fitted within these grooves. 65 The result is the formation of an exceed-

ingly rigid cylinder, the joints of which are very tight.

Furthermore, the segments 1^a are of such form that they are easy to roll or press into the shape shown, and therefore may be 70 formed of very hard rolled or pressed steel, such as chrome steel, and so may have the great durability or long life in service characteristic of such steel, as compared with cast iron or cast steel. 75

The heads, 2 and 3, are shallow, and therefore may be machined readily, both where they fit the ends of the segments 1^a and also over the surfaces of the radial ribs 11 and 12 formed integrally with head 3 which receive and support the grating segments 13. These grating segments may be of any usual construction, but preferably are of the construction of my application Serial No. 95,312, filed May 4, 1916. These grating 85 segments are held in place by wedge bars 14 (Fig. 8) and bolts 15. The heads 2 and 3 are held to the shell 1 by means of bars 16 engaging a number of bolts 7 which hold the shell segments together, and passing 90 through suitable apertures in said heads and provided, outside of such heads, with suitable clamping nuts. This provides a very rigid connection of the heads to the shell. 95

Each segment 1^a is seated at its ends in grooves 17 in the heads of the mill; whereby a very tight joint is formed between the shell proper and the heads.

In the construction shown in Fig. 1, each 100 segment 1^a of the shell and wearing member is formed with two halves of rises 8; each complete rise being formed of half rises of two adjacent segments. In the construction shown in Fig. 2, each segment 105 of the shell, which segments are here designated by numerals 8^b, is provided with a complete rise 8 located at about the center of the segment. The two constructions are substantial equivalents one of another, and 110 either may be employed as preferred.

Any suitable means may be employed for pressing the several bars of the grate sections 13 toward the center and so for holding those grate bars rigidly. I have illustrated, in the drawings, but particularly in Fig. 6, a preferred construction wherein the discharge head 3 of the mill has fitted into it segments 18 each having an oblique-faced rib 19 fitting into a corresponding 120 groove of the head 3. Wedge-headed bolts 20 such as shown in Fig. 7, fit into slots of the member 18 and pass through apertures of the head 3, and are provided outside of such head with suitable nuts, whereby 125 they may be drawn up. Owing to the wedge-shape of the heads of these bolts 20, and the corresponding wedge-shape of the bottoms of the slots in segments 18 in which such wedge-shaped heads fit, drawing up 130

these bolts 20 presses the bars of the grate segments together.

In Fig. 8 I have shown improved means for clamping the grate bars of the grate segments 18 down upon the ribs 11 of the head 5 3. The grate bars, here designated by numeral 21, are provided at their ends with oblique steps 22; and between the ends of the grate bars 21 of adjacent grate segments 10 13 correspondingly stepped clamping bars 14 are placed. It will be clear that by drawing down these bars 14 by means of the bolts 15 the grate bars 21 are held firmly at their ends.

15 What I claim is:

1. A ball mill such as described comprising a cylindrical wearing member formed of a plurality of segments, bolts connecting said segments, heads for said cylindrical member, and bars directly engaging the said bolts and secured to said heads.

2. A ball mill such as described comprising a cylindrical combined wearing member and shell formed of a plurality of radial segments secured one to another, heads secured to said cylindrical member, one of said heads having a discharge opening near its center and having integral ribs on its inner face, and a grating seated directly on 25 said ribs and secured to such head, the construction being such that because the said heads are separate from the said combined wearing member and shell the faces of said ribs adjacent said grating may be machined 30 readily.

3. A ball mill such as described comprising a shell with at least one separable head, said head having a grating-support, and a grating on such support comprising a series 40 of segments each formed of a plurality of grate bars, and means for pressing such grate bars inward and together comprising wedge-headed bolts extending to the exterior of the head and means for drawing 45 such bolts outward.

4. A ball mill such as described comprising

ing a head having a grate-support provided with a groove and a grating on such support comprising a series of radial segments each formed of a plurality of grate bars, 50 ring segments located across the ends of such grate-segments and each seated in said groove of such grate support, and wedge-headed bolts seated in such ring segments and pressing against the outer bar of the 55 corresponding grate segment and adapted to press the grate bars of that grate segment together.

5. A ball mill such as described comprising a head having a grate-support and a 60 grating on such support comprising a series of radial segments each formed of a plurality of grate bars, ring segments located across the ends of such grate segments and each seated in a groove of such grate support and provided with an oblique-faced rib fitting into a correspondingly oblique-faced 65 groove of such support, and wedges working against such ring segments and also against the outer bar of the corresponding grate 70 segments and adapted to press the grate bars of that grate segment together.

6. A ball mill such as described comprising a head having a grate-support having ribs, and a grating on such support comprising 75 a plurality of radial segments each comprising a plurality of grate bars the ends of which rest upon such ribs and are provided with oblique steps, correspondingly obliquely-stepped clamping bars fitting between the ends of the grate bars of adjacent 80 grate segments and having their oblique steps resting upon the oblique steps of the corresponding grate bars, and means for holding such clamping bars down.

In testimony whereof I have signed this specification in the presence of two subscribing witnesses.

FERDINAND E. CANDA.
